SEWING MACHINE LIGHTING FIXTURE

Kenneth Perkins, Scotch Plains, N. J., assignor
to The Singer Manufacturing Company, Elizabeth, N. J., a corporation of New Jersey

Application February 8, 1941, Serial No. 377,982

10 Claims. (Cl. 240—2.14)

This invention relates to electric lighting fixtures, more particularly of the sewing machine illuminating type, and has for an object to provide a simple and inexpensive construction comprising an easily effected assembly of component parts which may be readily molded.

A further object of the invention is to provide, in a lighting fixture as above described, an improved lens-mounting to facilitate insertion and removal of the lens.

A still further object of the invention is to provide an improved ventilating arrangement for the lighting fixture to prevent overheating of those external parts of the fixture likely to be touched by the operator.

A further purpose of the invention is to provide an improved assembly of shade, lens, reflector and light source for producing general illumination as well as spot illumination adjacent the needle of a sewing machine.

With the above and other objects in view, as will hereinafter appear, the invention comprises the devices, combinations and arrangements of parts hereinafter set forth and illustrated in the accompanying drawings of certain specific embodiments of the invention, from which the several features of the invention and the advantages attained thereby will be readily understood by those skilled in the art.

In the accompanying drawings, Fig. 1 is an elevational view of a sewing machine having mounted on its rear side a lighting fixture embodying the invention.

Fig. 2 is a fragmentary sectional view of a portion of the sewing machine arm showing one means for attaching the lighting fixture thereto.

Fig. 3 is an elevational view of a mounting bracket assembly for a lighting fixture.

Fig. 4 is a longitudinal sectional view, partly in elevation, of an improved lighting fixture.

Fig. 5 is a vertical section on the line 5—5, Fig. 4.

Fig. 6 is a left end view of the device shown in Fig. 4.

Fig. 7 is a top plan view of the device shown in Fig. 4.

Fig. 8 is a bottom fragmentary view of the switch-housing portion of the upper half of the lighting fixture showing the switch mechanism therein.

Fig. 9 is a partial bottom view of a portion of an improved lighting fixture showing means for receiving a mounting bracket.

Fig. 10 is an enlarged detailed sectional view on the line 10—10 of Fig. 4.

Fig. 11 is a disassembled perspective view showing the upper and lower sections of the lighting fixture with a part of the reflector in place in the upper section.

5 Referring more particularly to the drawings, Fig. 1 portrays a lighting fixture 1 embodying the invention mounted on the rear side of a sewing machine, comprising the cloth-plate 2, and a frame including a standard 3, bracket-arm 4 and head 5.

As shown most clearly in Figs. 2 and 3, a preferred means of attaching the lighting fixture 1 to the sewing machine is by a lighting fixture support comprising a bracket 6 and a saddle-arm 10. The bracket 6 is fitted within a recess 7 in the frame beneath a cover-plate 8, which closes an inspection opening 8^a in the standard 3, and is secured in said recess by means of the single screw 9 in the manner shown and described in the patent to Chason, No. 1,546,619 of July 21, 1925.

25 Adjustably secured to the free end of the bracket 6, as by a single screw 12, is a transversely positioned saddle-arm 10, the outer end 25 of which is fitted between ribs 11 formed integrally with the lower one of two portions of the lighting fixture later to be described. A screw 48 passing through a slot 50 in the saddle-arm 10, and threaded into the lower externally semi-cylindrical section 44 of the lighting fixture, 30 permits rotational adjustment thereof within the limits of the slot 50, and secures the fixture to the arm as shown best in Fig. 3. Thus the lighting fixture is rigidly yet adjustably secured upon the machine frame and extends horizontally along the rear side of the arm thereof.

35 More specifically, as shown in Fig. 4, the lighting fixture itself comprises an upper inverted trough-shaped element 13 and a lower frame-shaped lens-receiving element 14, preferably made of "Bakelite" or some other suitable molding material and adapted to be interfitted along the horizontal parting line 15. These parts are secured together by means of wire snap-rings 16, 17 and a screw 18 passing freely through an aperture 14^a in the forward end of the frame element 14 and threaded into a complementary aperture 13^a in the shade element 13, Fig. 11.

50 The shade element 13 is formed, at one end, with an externally semi-cylindrical switch-housing portion 19, shown in Figs. 4 and 7, which contains a well known switch mechanism, comprising the spring contacts 20, 21 and complementary movable contact 22, shown in Fig. 8.

Located in a pocket formed by the portions 48 on the shade member and the portion 49 on the lens-receiving member, is a metal, screw-threaded lamp-socket 46 having slots 51 which are engaged by the lugs 45, formed on said portions, to position and secure the socket in the lighting fixture when the shade element and the lens-receiving element are assembled together.

To control the turning on and off of a lamp 24 threaded into the socket 46, a turn button 23, extending vertically from the upper switch-housing portion, is operated to actuate the movable contact 22 of the switch mechanism.

The shade element 13 and the lens-receiving frame element 14 are connected together along a horizontal line by means of a light-tight joint shown in section in Fig. 5 and in more detail in Fig. 10. This joint comprises ribs 25 on the shade element, which ribs are received in complementary notched portions 26 provided in the inner edge of the frame portion of the lens-receiving element, thereby preventing interior light from leaking out laterally to the exterior of the lighting fixture.

A semi-cylindrical reflector 27, preferably of metal, positioned between the lamp 24 and the shade element 13, is formed with extended ears 28 which are received in slots 29 in the shade element and in recesses 30 in the lens-receiving element 14. These ears are held between the overlying wall of the slots 29 in the shade element and the underlying wall 47 of recesses 30 in the lens-receiving element, thereby securing the reflector 27 in proper position relative to the lamp 24.

A lens 33 is formed with lateral edge flanges 32 which are slidably confined between the shoulders 31, formed along the inner edges of the lens-receiving element 14, and the overlying ribs 25 of the shade element 13. The rear edge 36 of the lens 33 is vertically flat and engages, in abutting relation, the shoulders 37, Fig. 11; which are formed on the lens-receiving element to provide a limiting stop for the lens. A recess 43, located in the front edge of the lens 33, is engaged by the downturned portion of a spring detent 41 secured in a slot 42 under the head of the screw 18 to yieldingly hold the lens in operative position in the lighting fixture. There is thus provided means whereby a simple and easy insertion and removal of the lens from the lighting fixture may be effected by merely sliding the lens along the supporting guideway shoulders 31. The lens 33 is preferably formed with a semi-cylindrical lateral exterior surface 34 and a semi-spherical end surface 35.

To prevent overheating of the lighting fixture, a cut-out portion 38 in the lens-receiving element, to the rear of the lens, provides an inlet for cooling air which circulates freely, as shown by the arrows in Figs. 4 and 5, around the reflector 27 and lamp 24 absorbing heat therefrom and which, by natural convection, is expelled from the interior of the lighting fixture by way of the outlet slits 39 in the top and the apertures 40 in the end of the shade element, Fig. 6.

From the foregoing it will be perceived that I have provided an improved and simplified lighting fixture for sewing machines comprising a plurality of readily moldable parts which may be assembled readily and held together by simple connectors; in which the lens is removably supported in its operative position; and in which

provision is made to prevent overheating of the device.

It will be obvious to those skilled in the art that the invention may, without departure from its essential attributes, be embodied in various specific forms other than those shown and described, which latter are to be considered in all respects as illustrative of the invention and not restrictive; reference being had to the appended claims rather than to the foregoing description to indicate the scope of the invention.

Having thus set forth the nature of the invention, what I claim herein is:

1. A lighting fixture having a lamp-socket and lamp, comprising two horizontally disposed relatively interfitting components, one forming an upper shade element containing top and end apertures, the other forming a lower lens-receiving element having a bottom aperture and inturned edge portions, a lens having complementary out-turned flanged edge portions slidably positioned within said inturned edge-portions of the lens-receiving element and a reflector positioned intermediate the two components, said apertures providing means for ventilating the lighting fixture.

2. A lighting fixture having a lamp-socket and lamp, comprising two longitudinally disposed relatively interfitting components made from insulating material, one forming a trough-shaped shade element, the other forming a lens-receiving element provided with inturned edge portions, a lens having complementary out-turned edge portions slidably and releasably secured within said inturned edge portions of the lens-receiving element, and a reflector positioned intermediate the two components.

3. A lighting fixture construction having a lamp-socket and lamp, comprising two longitudinally disposed interengaging components, one forming a trough-shaped lamp-shade element having a switch-housing portion, the other forming a complementary generally rectangular frame element provided with inturned edge portions and having a switch-housing portion, and a light-transmitting member having complementary out-turned edge portions slidably and releasably positioned within said inturned edge portions in the frame of the rectangular frame element.

4. An electric lighting device having a lamp-socket and lamp, comprising two longitudinally disposed interfitting components, one forming an inverted trough-shaped shade element, the other forming a lens-receiving element having laterally inturned edge portions, means for securing said elements together, a lens having complementary out-turned edge portions slidably and removably positioned on said edge portions in the lens-receiving element and a reflector positioned within the shade element.

5. A lighting fixture having a lamp-socket and lamp, comprising a shade member and a lens-receiving member having relatively interengaged edge portions formed along a longitudinal peripheral parting-line, said lens-receiving member having an open, rectangular frame portion and an adjoining switch-housing portion, a lens having edge portions slidably and removably confined by the interengaged edge portions of said shade and lens-receiving members, and a reflector positioned intermediate said shade and lens-receiving members and secured at points between said edge portions.

6. A sectional lighting fixture having a lamp-

socket and lamp, comprising two separable sections forming a shade member and a lens-receiving member having integral interengaging longitudinal edge formations preventing relative horizontal movement thereof, said lens-receiving member having an open, rectangular frame portion and an adjoining switch-housing portion, a lens positioned with its edge portions intermediate the edge portions of said shade and lens-receiving members, and a reflector positioned intermediate said shade and lens-receiving members.

7. A sewing machine lighting fixture having a lamp-socket and lamp, comprising a split casing affording upper and lower separable sections, the upper of said sections having a lamp-shade portion and an adjoining switch-housing portion, the lower of said sections having a switch-housing portion and an adjoining open frame portion which is in juxtaposition with the horizontal edge of the lamp-shade portion of the upper section of said casing, and a lens element having edge portions confined by the juxtaposed lamp-shade and open frame portions of the separable sections of said casing.

8. In a sewing machine lighting fixture having a lamp-socket and lamp, a longitudinally split casing affording upper and lower juxtaposed separable sections, the upper of said sections having an inverted trough-shaped lamp-shade portion and an adjoining recessed switch-housing portion, the lower of said sections having a switch-housing portion and an adjoining open frame portion formed with an edge which interengages the horizontal edge of the lamp-shade portion of the upper section of said casing, and

5 a light-transmitting element having integral edge portions removably confined by the complementary edges of the juxtaposed lamp-shade and open frame portions of the separable sections of said casing.

9. A lighting fixture having a lamp-socket and lamp, for a sewing machine comprising a longitudinally split casing affording two separable sections disposed in juxtaposition, one of said sections having a lamp-shade portion and an adjoining switch-housing portion, the other of said sections having a switch-housing portion and an adjoining open frame portion which is in juxtaposition with the longitudinal edge of the lamp-shade portion of one section of said casing, and a lens element having edge portions releasably confined by the juxtaposed lamp-shade and open frame portions of the separable sections of said casing.
